BATHTUB TOY

Frank Kohner, New York, N.Y., and Albert Stubbman, Franklin Lakes, N.J., assignors to Kohner Bros., Inc., Paterson, N.J., a corporation of New York

Filed Feb. 27, 1969, Ser. No. 15,959

Term of patent 14 years

Int. Cl. D21—02

U.S. Cl. D34—15

FIG. 1

FIG. 10

FIG. 9

FIG. 2

FIG.3

FIG.4

FIG.7

FIG. 1 is a front perspective view of the bathtub toy, the perspective being partly exploded in that the shower cup is pulled forwardly out of its normal receptacle;

FIG. 2 is a front view of the bathtub toy;

FIG. 3 is a left side view of the bathtub toy;

FIG. 4 is a right side view of the bathtub toy;

FIG. 5 is a top plan view of the bathtub toy;

FIG. 6 is a bottom view of the bathtub toy;

FIG. 7 is a developed view of the carousel rotor;

FIG. 8 is an auxiliary view taken substantially along the line 8—8 of FIG. 2, and illustrating, in full face, the spouting figurine;

FIG. 9 is a top view of the shower cup; and

FIG. 10 is a bottom view of the shower cup.

We claim:

The ornamental design for a bathtub toy, substantially as shown and described.
